ELECTRIC FLASHING SIGN

Clint E. Thomas, Lemon Grove, Calif.

Application December 10, 1956, Serial No. 44,127

Term of patent 14 years

(Cl. D1—12)

Fig. 1 is a top perspective view of the electric flashing sign showing my new design.

Fig. 2 is a side elevational view thereof, showing the top side of the electric flashing sign; and

Fig. 3 is a transverse sectional view taken on line 3-3 of Fig. 2, showing that the top and bottom side of the flashing sign are the same.

I claim:

The ornamental design for an electric flashing sign, as shown and described.
